JOSEPH HIRSCH, OF YONKERS, NEW YORK, ASSIGNOR TO KOPS BROS. INC., A CORPORATION OF NEW YORK.

ELASTIC WEBBING.

Application filed February 1, 1927. Serial No. 165,058.

This invention relates to an improvement in elastic webbing and more particularly to that type of elastic webbing adapted for use as inserts or sections of corsets, brassières, 5 girdles and other similar garments for women's wear. In the use of ordinarily constructed elastic webbing or fabric for the purposes indicated, there is a tendency for the elastic strands to pull through the fabric due either to being pierced or severed by the sewing needle by which the fabric is secured to the body of the garment or by the elastic strands pulling through the fabric itself. In either event, as will be appreciated, the fabric loses its elasticity and cannot then perform its intended functions in the garment. I am aware that heretofore, elastic webbing has been woven, knitted or made otherwise in such a manner as to permanently bind the elastic strands in predetermined sections to overcome the difficulty of severing the elastic strands in sewing the fabric to the body of a garment and to prevent the elastic strands from pulling through 25 the fabric. In accordance with my present invention, however, the elastic webbing is constructed in the usual manner either by weaving, knitting, or otherwise, and the elastic strands employed are covered in a peculiar manner in order to permit the same to retain their relative positions in the finished article. In carrying out the invention each elastic strand is preferably provided with a knotted thread forming a cover or a part of 30 the cover therefor and in addition to the knotted thread the cover may include additional ordinary threads. The elastic strands thus prepared are woven or knitted or otherwise worked into the elastic webbing and 35 the action of the knotted thread forming projections or bumps on the surface of the elastic strands with the elastic strand itself and the body of the fabric into which it is worked causes the elastic strand to retain its 40 position in the finished article, as will be hereinafter more particularly described.

In the drawing Figure 1 is a diagrammatic plan showing an elastic webbing made in accordance with my present invention.

Fig. 2 is an elevation showing an elastic strand provided with a knotted thread wound thereon.

Fig. 3 is a view similar to Fig. 2 showing the elastic strand with both a knotted and a plain thread wound thereon. In Figs. 2

and 3 the elastic strand is illustrated as under tension for the application of the winding of the threads thereon.

Fig. 4 is an elevation of an elastic strand after the tension is released showing the cover formed of a knotted and a plain thread, and

Fig. 5 is a section on line 5—5, Fig. 4.

Referring to the drawing it will be seen that in carrying out the invention the elastic webbing made in accordance therewith may be woven in the usual manner to include inelastic warp threads 10, inelastic weft threads 11 and spaced elastic warp threads 12. The fabric, however, may be knitted or constructed in any other manner and the elastic strands may be utilized as wefts instead of warps without departing from the nature of the invention.

In carrying out the invention the elastic strands employed are specially prepared. Each elastic strand is wound while under tension with a knotted thread or a thread similarly prepared. As indicated in Fig. 2, a knotted thread is indicated at 13 and provided at regular or irregular intervals with knots 14. This thread is wound so as to form a cover for the core of the elastic strand. The knotted thread is preferably wound spirally, although as will be understood this is not absolutely necessary. As shown in Fig. 3 in addition to the knotted thread the elastic strand while under tension may be wound with a plain or ordinary thread 15 which is preferably wound spirally and in the direction opposite to that in which the knotted thread is wound. However, the particular manner in which the additional thread is wound does not enter into or form part of this invention. It will be equally obvious that while I have illustrated a cover formed of a single knotted thread as shown in Fig. 2 or a cover formed of a knotted thread and a plain thread, any desired number of threads either knotted or plain may be employed to form a cover for the elastic strand which when released produces a strand as illustrated in Fig. 4 in which the knotted portion of the knotted thread form projections at intervals preferably irregularly placed in the surface of the strand. Also as illustrated in Fig. 5, it will

be understood that the knotted thread or its equivalent is wound on the rubber or other core of the strand, while under tension, so

as to conform with its surface and that when the tension is released the knotted portions of the thread tend to provide indentations in the core as indicated at 16 in Fig. 5 of the drawing. It will furthermore be understood that in weaving or knitting or otherwise working the elastic strands as hereinbefore described into the elastic webbing, the inelastic warp and weft threads or 10 the inelastic threads employed otherwise than in weaving, conform to the surface of the elastic strand whereby the irregularities in the surface of each strand due to their association with the rubber core and the 15 inelastic strands of the fabric prevent the elastic strand from pulling through the finished article.

It is also to be understood that by the term knotted thread or a thread having knotted portions therein applicant means any thread in which at stated intervals there are enlarged portions of the thread.

I claim as my invention:

1. An elastic strand comprising a core,

and a cover thread having knots therein at 25 relatively close intervals.

2. An elastic strand comprising a rubber core, and an inelastic thread having knots therein at relatively close intervals.

3. An elastic strand comprising a rubber 30 core, a thread wound spirally thereon and having knots therein at relatively close intervals, and a plain inelastic cover thread surrounding the core and the spaced knotted thread.

4. In an elastic webbing, inelastic warp and weft threads, and a plurality of elastic threads each comprising a core and a cover 35 thread having knots therein at relatively close intervals.

5. In an elastic webbing, inelastic warp and weft threads, and a plurality of elastic warp threads each comprising a rubber core and a cover thread in which there are knots 40 at relatively close intervals.

Signed by me this 14th day of January, 1927.

JOSEPH HIRSCH.
